UNITED STATES PATENT OFFICE.

ADOLPH L. NELSON, OF INDIANAPOLIS, INDIANA.

FUEL VAPORIZER.

Application filed November 5, 1920. Serial No. 422,080.

My said invention consists in an improved construction of devices for improving, or aiding in the vaporization and mixture of fuel used in internal combustion engines, whereby the liquid fuel is completely vaporized before being drawn into the intake manifold of the engine, all as will be hereinafter more fully described and claimed.

Referring to the accompanying drawings which are made a part hereof and on which similar reference characters indicate similar parts,

Figure 1 is a view of the upper end of a vertical type "valve-in-the-head" engine, equipped with my invention, and

Figure 2, a detail view showing the part constituting the principal feature of the invention in perspective.

In said drawings, the portions marked A represent the engine cylinder, B the carburetor, C the vaporizer forming a leading feature of my said invention, D the intake manifold, and E the exhaust manifold of the engine.

All of the parts above referred to, except the vaporizer C, are of standard construction as in use in types of internal combustion engines now in common use, or may be of any appropriate construction and arrangement.

The vaporizer comprises a casing formed appropriately to be interposed between the carburetor B and the inlet pipe of the intake manifold D. It is preferably formed as an elbow, one end connected by clamping bolts 10 to the upper end of the carburetor B and the other end connected by clamping bolts 11 to the outer end of the inlet pipe of the intake manifold. It is formed with a central enlarged portion 12 and an annular partition 13 with circumferential corrugations or fins, between the sides of said enlarged portion, forming a chamber 14 surrounding the corrugations and positioned at the angle of the casing. The ribs or fins of the corrugations extend both into chamber 14 and also into the interior of the passageway from the carburetor to the intake manifold. A pipe 15 connects with the casing of said part C and with a branch pipe 16 which is connected with the exhaust manifold E. Another pipe 17 leads from the opposite side of chamber 14 to a fitting 18 also connected with the exhaust manifold E. A valve 19 is mounted in the pipe

leading from manifold E to the fitting 18, which connects with the exhaust pipe 20 which may lead to any point desired. Said valve 19 is mounted upon a shaft operated through the medium of a crank-arm 21 and a connecting rod 22, which may lead to a point convenient to the chauffeur for its operation.

In operation, the valve 19 being closed, or partly closed, the hot gases from the exhaust manifold E pass through pipes 16 and 15 and around through the chamber 14 heating the corrugated partition 13 to a very high temperature, and then pass through pipe 17 and fitting 18 to the exhaust pipe 20. By the adjustment of valve 19, any proportion of the exhaust gases may be diverted through chamber 14 as desired. The fuel mixture coming through carburetor B is drawn through the passageway inside of vaporizer C forming an air stream containing liquid fuel in the form of fine drops or spray, and also containing some fuel vapor. As is well known the liquid will seek the points of lowest velocity and the air will seek the point of highest velocity or least resistance. This tendency operates to throw the liquid to the outside of the stream, and the spray of the liquid fuel will strike the ribs of the partition 13 on the upper side and be retarded and thoroughly vaporized before passing with the air to the intake manifold. Any liquid not vaporized is caught within the grooves between the ribs and will flow to the lower side of the corrugated section and be vaporized by the heat before passing out with the air to the intake manifold. In this manner, the vaporization of all liquid fuel is insured before it reaches the cylinders of the engine with the consequent beneficial results on the fuel and with the assurance that all of said liquid fuel will be utilized. While the liquid fuel is thus subjected to the heat of the extended area of the corrugated section and its passage to the cylinders in liquid form prevented, the air drawn through this channel will not be overheated because of the very short length of the heated section and the small area thereof, the edges of the ribs, coming in contact therewith. Thus the air will not be unduly expanded but left at a temperature that will combine the hydrocarbon vapor at a temperature to form a comparatively heavy mixture of the highest

quality and efficiency for use, and not expanded to a temperature that would result in loss of power.

Having thus fully described my said invention, what I claim as new and desire to secure by Letters Patent, is:

1. In an internal combustion engine, a tubular vaporizer open at both ends adapted to be inserted between the carbureter and the intake manifold whereby the current of fuel-laden air passes axially through the same from end to end, said vaporizer having wide, relatively thin inner fins at right angles to the direction of flow of the air stream providing a large contact area for liquid and a small area of contact for the air in the stream of mingled air and liquid fuel said fins also acting as baffles for the outer liquid-laden part of said stream, and means for heating the vaporizer, substantially as set forth.

2. In an internal combustion engine, a vaporizer adapted to be inserted between the carbureter and the intake manifold said vaporizer having a tubular inclined portion with inwardly inclined extending fins at right angles to the axis of said inclined portion with grooves between them to catch and hold liquid fuel, and means for heating the vaporizer, substantially as set forth.

3. In an internal combustion engine, an elbow-shaped vaporizer casing adapted to be inserted between the intake manifold and the carbureter said casing being inclined downward toward the carbureter, annular inner fins on the casing, and means for heating the casing substantially as set forth.

4. In an internal combustion engine, an elbow-shaped casing adapted to be attached to the intake manifold and inclined downward toward the carbureter, opposed sets of concentric inner and outer fins on the casing, and means for bringing the exhaust gases into contact with the exterior of the casing, substantially as set forth.

5. In an internal combustion engine, an elbow-shaped inclined casing adapted to be inserted between the carbureter and the intake manifold said casing having a double wall at the bend therein, inner and outer sets of concentric fins on the inner wall at said bend, and connections from the engine exhaust to said chamber whereby a relatively short section of the fuel passage is heated for vaporizing the liquid fuel with-

out excessive heating of the air mingled therewith, substantially as set forth.

6. A vaporizer adapted to be inserted between the carbureter and the intake manifold of an internal combustion engine, comprising an elbow-shaped casing, means for heating a narrow zone thereof at the bend of the casing, and circumferential grooves in said zone for retaining unvaporized fuel in contact with the heated wall of the casing, substantially as set forth.

7. A vaporizer adapted to be inserted between the carbureter and the intake manifold of an internal combustion engine comprising a tubular member having an upwardly inclined portion, circumferential inclined fins in a narrow zone on said portion, and means for heating said zone, substantially as set forth.

8. A fuel vaporizer comprising a tubular member providing a single large passage for the air stream passing through the vaporizer, a series of thin, wide annular flanges arranged in a zone about the interior of said tubular passage, and means for heating said zone only whereby liquid fuel held between said flanges is vaporized while also serving to insulate the air stream against the heat from said heating means, substantially as set forth.

9. A fuel vaporizer comprising a tubular member providing a single large passage for the air stream passing through the vaporizer, a series of thin, wide annular flanges arranged in planes perpendicular to the air stream in a zone about the interior of said tubular member, and means for heating said zone, substantially as set forth.

10. A fuel vaporizer comprising a tubular member providing a relatively large passage for the air stream passing through the vaporizer, a series of thin, wide annular flanges arranged in planes perpendicular to the air stream in a relatively narrow zone about the inner periphery of said tubular member, external annular flanges in the same plane with the respective inner flanges, and means for heating said zone, substantially as set forth.

In witness whereof, I have hereunto set my hand and seal at Indianapolis, Indiana, this 30th day of October, A. D., nineteen hundred and twenty.

ADOLPH L. NELSON. [L. s.]
